UNITED STATES PATENT OFFICE.

DAVID G. McCAA, OF LANCASTER, PENNSYLVANIA.

APPARATUS FOR THE PRODUCTION OF HIGH-FREQUENCY CURRENTS OF ELECTRICITY.

1,247,556.

Specification of Letters Patent.

Patented Nov. 20, 1917.

Application filed January 14, 1914. Serial No. 812,051.

To all whom it may concern:

Be it known that I, DAVID G. McCAA, a citizen of the United States, residing at Lancaster, in the county of Lancaster and State of Pennsylvania, have invented certain new and useful Improvements in Apparatus for the Production of High-Frequency Currents of Electricity, of which the following is a specification.

10 My present invention has for its object the provision of continuous high frequency currents of electricity, which, while applicable for use to very many of the arts commonly employed at the present time, is yet more particularly designed for and adapted to be employed in connection with systems which have for their especial purpose, the transmission of signals,—radiotelegraphy,—and of spoken speech,—radiotelephony,—between 15 points, or stations located at distances, often great, from each other, without the employment of conductors of electricity of any material whatsoever, other than atmospheric air, and to such end the invention contemplates, among other ends, the provision of 20 means whereby an ordinary pulsatory current, of low frequency and low electro-motive force, is changed, or transformed into a current of high frequency oscillations and 25 high electro-motive force, to the attainment of which end the invention consists, in the construction, arrangement and combination of the several parts comprised therein for service and the operation of the same to the 30 end named, substantially as is hereinafter described and illustrated in the accompanying drawings, wherein:

Figure 1, illustrates in a diagrammatic view, an electric circuit comprising in a 40 single operating system, a current generating circuit, a current transforming circuit and a current transmitting circuit, each thereof including devices peculiar to the circuit of which they are a part, and all connected and arranged in accordance with my invention.

Fig. 2, illustrates in a simple diagrammatic view, the armature windings of the generator preferably employed in the present embodiment of my invention.

Fig. 3, is a like diagrammatic view, illustrating the manner in which the step up transformer primaries are connected in the present embodiment of my invention.

Fig. 4, shows, in a diagrammatic view, the 55 position, as regards each other, of the primaries of the step up transformers employed in my invention, and the manner in which said primaries are traversed by a three phase current from the generator.

Fig. 5, shows in side elevation, the current 60 interrupting device which operates, within the spark gap included in the circuit between the secondaries of the step up transformers and primary of the air core transformer, to 65 interrupt and break up current crossing said gap, in the form of sparks.

Fig. 6, is a top plan view of the interrupting device illustrated in Fig. 5.

Fig. 7, shows, in a detail plan view, a 70 portion of the interrupting device illustrated in Fig. 5, interposed between a pair of multiple point electrodes, and the interrupted sparks as they appear when the device is in action.

Fig. 8, illustrates in a detail plan view, a 75 portion of each of a plurality of interrupting devices, located between multiple point electrodes, and moving in opposite directions, said view showing the interrupted 80 sparks, as they appear when the device is in action.

Fig. 9, illustrates in a detached detail view, a part of the interrupting device, in full size.

Fig. 10, shows in a detached detail view, a part of an interrupting device similar in form to that shown in Fig. 9, but adapted to 85 more rapidly break up current crossing the spark gap.

Figs. 11, to 13, inclusive, illustrate different types of air core coils which may be employed in my invention, and

Fig. 14, shows a modification of the oscillatory circuit and the connection of the same 95 with the transmitting circuit.

The invention which forms the subject of the present application for Letters Patent, is, in the main, identical with that which formed the subject of an application filed 100 by me on the 27th of January 1911, numbered 605,054, and abandoned October 3rd, 1912, and said present application, or invention, in common with that set forth in the abandoned application referred to, contemplates the provision of means, whereby an ordinary pulsatory, that is to say, an alternating, current of electricity, of low 105

electro-motive force, is changed, or transformed, into a current of high frequency oscillations, of high electro-motive force, for use in connection with radiotelegraphic and 5 radiotelephonic systems, for the transmission of signals and of spoken speech, between stations separated by a greater, or a less degree of space, without the employment 10 of conductors, of any material whatsoever other than the natural media.

To the attainment of the end above named, many inventions have been made, each thereof employing as the main agent to the accomplishment of the purpose noted, some 15 device either mechanical, or otherwise, possessing qualifications necessary to bring about the interruption of the current of electricity at some point between the source of such current, and the point at which it is 20 impressed upon the transmitting devices, which it is to energize.

It is to be understood that the successful operation of the inventions noted, to the ends sought thereby depends wholly upon 25 the extent to which the current has been broken up, or interrupted between the points named and before it has been impressed upon the transmitting circuit.

In common with the inventions above referred to, the present invention has for its 30 main purpose, the provision of devices through and by which current from a source of supply, may be so highly interrupted as to positively insure the attainment of the 35 end sought thereby.

Referring to the drawings wherein similar letters and numerals of reference denote similar parts, A, designates that part of my present invention which may be termed the 40 current generating, or primary circuit, B, that part which may be termed the current transforming, or secondary circuit and C, that part which may be termed the transmitting, or sonorous circuit, and it is to be 45 understood that the several circuits above named, are interdependent upon each other to the end that the purpose of the invention may be realized.

In carrying my present invention into 50 practice, I preferably employ a three phase generator D, that is to say, a generator having three windings upon its armature, each thereof distinct and independent of the other and each adapted to deliver a current 55 of electricity over a circuit peculiar to itself, and I arrange that said windings, for the purposes of said present invention, shall be placed upon the armature of the generator D, in accordance with the Δ scheme of connection, as indicated in Fig. 2.

I employ, in connection with the generator D, three independent step up transformers E, F and G, preferably using the Y scheme in connecting the respective primary 65 and 2 and 3, of said transformers,

through suitable conductors 4, 5 and 6, with the armature phase rings 7, 8 and 9.

I provide the conductors 4, 5 and 6, between the generator D, and the transformers E, F and G, with a three pole switch 70 10, to simultaneously close circuit, through said conductors, between said generator and transformers.

The several devices and connections therebetween as last above described, constitute 75 the current generating, or primary circuit A, hereinbefore referred to and the operation of said devices, as well as the result of such operation upon the remaining elements comprised in my invention, will be presently 80 explained.

Having described the several devices which are comprised in the generating, or primary circuit A, I will now proceed to describe those which are comprised in the 85 current transforming or secondary circuit B, which circuit includes, as the source of energy the secondaries 11, 12 and 13, one pole of each of which, is connected to a conductor 14, which extends thence to one pole 90 of the primary 15, of an air core transformer H.

I connect the opposite pole of the primary 15, through a common lead, or conductor 16, with three independent conductors 17, 18 and 19, and provide said conductors, at their free ends, with the inductance coils 20, 21 and 22, and from said coils I extend conductors 23, 24 and 25, which terminate in multiple point electrodes 26, 27 100 and 28, that are arranged in a common plane, see Fig. 1.

I provide the poles of the secondaries 11, 12 and 13, which are opposite those connected to the common conductor 14, with 105 conductors 29, 30 and 31, which terminate in multiple point electrodes 32, 33 and 34, that are arranged in a common plane opposite to and at a short distance from the multiple point electrodes 26, 27 and 28, see 110 Fig. 1.

I provide each of the conductors 29, 30 and 31, with a condenser 35, 36 and 37, respectively, arranging each thereof, in series with the gap formed in the circuit of which 115 each conductor is a part.

It is to be understood that the space between each of the opposing multiple point electrodes, forms the spark gap that is essential to the operation of oscillatory circuits, such as is herein shown, also that each of such gaps may be lengthened or shortened to increase, or to diminish the dielectric resistance of the spark gap, to the passage 120 of current thereacross as may be desired, further, that adjustment of said electrodes may be made by any desired means suitable to the end sought. The electrodes 26, 27 and 28, and 32, 33 and 34, may be made of 125 any desirable material and in any desired 130

form and type, that will meet and fulfil the conditions that must absolutely obtain in each thereof, that is to say, having a body portion provided with projecting points, 5 which body and points shall be free conductors of electricity.

For the purposes of the present invention, I provide that the electrodes noted shall each consist of a plate 38, provided upon 10 one of its edges with a series of projections 39, and upon its opposite edge with a screw threaded rod 40, which rod is securely connected to the body portion 38, and extends thence in suitable supports hereinafter 15 noted.

The transmitting or sonorous circuit C, comprises the secondary 41, of the air core transformer H, and the antenna 42, in which latter for the purposes of the present invention, 20 I include current interrupting mechanism, which in the present instance, consists in a rotatable plate 43, mounted upon a shaft 44, which is provided with a pulley 45, to be turned by a belt 46, from any desired source 25 of power, and I provide said plate with studs 47, which, extending through said plate project from the opposite sides thereof and are arranged to pass through a gap 48, formed in the antenna 42, to close circuit 30 therethrough, when the plate 43 is rotated.

It will be understood that the plate 43, is to be made of a suitable non-conducting material, also that the studs 47, which extend through and from the opposite sides of 35 said plate, shall be made of a suitable conducting material, and further that such studs shall be so proportioned as to length, that they shall extend nearly into contact with the opposite sides of the gap 48, formed in 40 the antenna 42.

From the arrangement and combination of the several elements comprised in my invention as so far described, it will be understood that current from the generator D, 45 will, because of the peculiar winding of the armature of said generator and the connection thereof with the primaries 1, 2 and 3, of the respective transformers E, F and G, separately and successively energize said 50 primaries; that the energizing of said primaries will, in accordance with the law which obtains in the production of induced currents and which is as follows: viz. that the closing of circuit through the primary of an 55 induction coil, will operate to cause a rise of the magnetic flux in the core of said coil and thus induce electromotive force in the secondary of said coil in direction opposite to that of the primary, and contrariwise, that 60 the opening of circuit through the primary will operate in like manner to induce current in the secondary, but in direction like unto that of the primary,—will operate to successively energize the secondaries 11, 12 65 and 13, of said transformers E, F and G;

that each of said secondaries, 11, 12 and 13, will in turn transmit the current induced therein, by the primary 11, 12, or 13, peculiar thereto as noted, to the primary 15, of the air core transformer H, through the several 70 elements included in the conductors therebetween, thus energizing said primary; and that the latter named primary will through the operation of the law above set forth, induce a current in the secondary of said air 75 core transformer H, to energize the sonorous circuit.

It is to be understood that aside from the change of current from low potential, to high potential, which is consequent upon the 80 action of the step up transformers E, F and G, no material change in the current of electricity supplied to the primary 15, of the air core transformer H, would result from the operation of the several devices described, 85 that is to say, the current delivered to the primary 15, will not be changed in frequency beyond that denoted by the sum total of the frequencies of the transformers E, F and G, and inasmuch as such a change of 90 frequency is the end sought by the present invention, and the fact that such end can only be accomplished through the interruption of the current resulting from the operation of the devices hereinbefore described, 95 and further as such frequency depends upon the time interval of such interruptions, it has been deemed expedient to combine with the devices hereinbefore described, certain other devices hereinafter described, in order 100 that the full intent and purpose of the invention might be realized.

To the end named, I provide that the current produced in the circuit B, through the action of the devices hereinbefore described, 105 shall be rapidly interrupted, and to such end I place within the spark gaps, which are formed between the terminal points of the electrodes 26 and 32, 27 and 33, and 28 and 34, which are located upon opposite sides of the spark gaps noted, current interrupting mechanism, which may consist in independent devices each located between the opposite electrodes 26 and 32, 27 and 33, and 28 and 34, or, as is the case in the present instance, in which the terminal points of the several electrodes upon the same side of the spark gaps, are arranged in a plane common to each and all, of a single member, which, in the present invention, consists in a rotatable disk I, constructed of a suitable non-conducting material, which is mounted upon a shaft I', that is journaled, at opposite sides of the disk I, in supports J, J', which are secured to a common base K, at opposite 115 sides of the disk I.

I provide the shaft I', with a pulley L, to be turned by a belt L', from any desired source of power, (not shown herein) to rotate 120 said disk I.

I provide the disk I, near its periphery, with a series of apertures *i*, which formed through said disk extend in a plane concentric with the center of the disk, entirely 5 around the same, at equal distances from each other, as shown in Fig. 9.

I provide that the supports J and J', above the journals of the shaft I', shall extend nearly, or quite to the plane of the periphery 10 of the disk, and preferably form such extensions in three portions each, see Figs. 5 and 6, and provide each of such extensions, at points opposite to the apertures *i*, which are formed through the disk I, with apertures 15 for the passage of the screw threaded rods 40, of the multiple electrodes, 26, 27, 28, and 32, 33, 34.

I provide that the electrodes noted shall, when in position in their supports, be adjustable toward and from the disk I, to 20 which end I provide the supporting rods 40, of said electrodes, upon each side of the apertures in the supports J, J' in which said rods are mounted with screw threaded nuts 25 49 and 50, respectively, by the adjustment of which the said electrodes, may be moved toward and from the rotatable disk I, as will be readily understood.

I preferably form the rotatable disk I, of 30 large diameter, so that a great number of apertures *i*, may be formed therethrough, as is illustrated in Fig. 9, which shows, in full size, a portion of a disk of which the full diameter is 18 inches, and in which, the apertures *i*, are formed through the disk, each 35 one half inch distant from the periphery of said disk, and one twelfth of an inch distant, each from the other, so that said disk shall, when in position for operation contain a 40 large number of apertures *i*, in the present instance about 642, in all.

While I have, in the last above paragraph, set forth the dimensions of an interrupting disk, with the number of apertures formed 45 therethrough, which I have in practice, found to give results of high order, I yet do not wish to limit myself to disks of the dimensions noted and having the number of apertures shown, since results, which I have 50 already attained through the use of a disk of the dimensions noted, may be surpassed by disks of a greater or a less diameter and having a greater, or a less number of apertures formed therethrough, as for instance, 55 a disk, similar to that, of which a portion is shown in Fig. 10, in which the apertures are formed through the disk on a plurality of concentric circles, upon each of which such apertures are preferably separated for 60 a distance approximating that shown in Fig. 9, and so arranged, with reference to each other, that the apertures upon either of said circles, shall fall upon radial lines that would extend between the apertures formed 65 upon the remaining circles, by which ar-

rangement the number of apertures formed through a disk of the diameter hereinbefore noted, would be approximately many times that of the disk first above described.

Again I do not wish to limit myself to the use of but one disk between opposing electrodes, as I have found by practice, that results of great value follow and are consequent upon the employment of a plurality of disks, placed in axial alinement each with the other, and rotated in opposite directions, as is indicated by the arrows *s* and *t*, in Fig. 8, for reasons which will be hereinafter set forth.

It is to be understood that the inductance coils 20, 21 and 22, are included in the circuit which includes the secondaries 11, 12 and 13, of the transforming, or secondary circuit B, for the purpose of reducing to any desired extent, the normal high frequency of the apparatus hereinbefore described, so as to adapt it to the desired frequency of the antenna, to which end, said inductances are variable in character.

Figs. 2, 3 and 4, of the drawings, respectively represent in diagrammatic form, the construction and action of one, or more of the devices comprised in my invention and of said Figs. 2 and 3, respectively represent, the one Fig. 2, the manner of winding the 95 armature of the generator D, which figure shows the Δ scheme of connection; the other, Fig. 3, the manner of connecting the primaries of the step up transformers, with the armature of the generator, which figure 100 shows the Y scheme of connection, which connection is preferably employed for the reason that it shows higher efficiency in action.

In Fig. 4, the primaries of the transformers E, F, and G, are each represented by small rectangular figures which are successively arranged above and below a line *n*, *o*, common to all of said figures, thus primary 1, is indicated by the first rectangular figure 110 above the line *n*, *o*, primary 2, by the first figure below said line, primary 3, by the second figure above the line and so on successively, as is indicated by the reference numerals 1, 2 and 3.

In Fig. 4, referred to, I indicate the particular phase current which energizes each of the primaries, by a full line, a line composed of dashes and a dotted line respectively, thus the phase by which the primary 120 1, is energized is indicated by a full line 51, the phase by which the primary 2, is energized, is indicated by a line 52, composed of dashes and the phase by which the primary 3, is energized, is indicated by a dotted line 54.

By reference to Fig. 4, noted, it will be observed that the full line 51, passes successively about the outer end of the rectangular figure marked 1, both above and below 130

the line n , o , the dash line 52, about the figure marked 2, and the dotted line 53, around the figure marked 3, thus clearly indicating the course of the several phase currents.

5 It is to be understood that the curved portion of the lines 51, 52 and 53, about the rectangular figures 1, 2 and 3, noted, indicates the extreme distance to which potential rises in each of the primaries represented by said 10 figures, or in other words, the spark period of the secondaries 11, 12 and 13, which are respectively energized by said primaries.

Before describing the operation of my invention, I will briefly outline the several 15 phase circuits comprised therein, and the relation of each of said circuits to the other, using to such end the armature rings 7, 8 and 9, to denote such phases.

Proceeding, rings 7 and 8, denote phase 1, 20 rings 8 and 9, denote phase 2, and rings 9 and 7, denote phase 3, and of said phases that first named, phase 1, supplies primaries 1 and 2, the circuit starting at ring 7, thence running through conductor 4, to and through 25 primary 1, thence to and through primary 2, and thence to ring 8; phase 2, supplies primaries 2 and 3, the circuit starting at ring 8, thence running to and through primary 2, thence to and through primary 3, and thence 30 to ring 9; phase 3, supplies primaries 3 and 1, the circuit starting at ring 9, thence running to and through primary 3, thence to and through primary 1, and thence to ring 7.

The operation of my invention is as follows, viz: Let it be assumed that a current of desired voltage to energize the step up transformers E, F and G, is supplied by the generator D, that while such current may be of any desired low frequency, as for instance 40 25, 60, 125 or 133 cycles per second, let it be assumed that such current has a frequency of 60 cycles, or in other words, that the armature of the generator D, is rotated 60 turns per second and since said armature is, 45 as has been hereinbefore stated, three phase wound and each phase thereof connected to energize one of the primaries 1, 2 and 3, of the transformers E, F and G, it follows, that each of said primaries will be energized once, each time the armature is rotated, and that the time period between the energizing of said primaries will be equal, each with the other, so that, while the frequency of the current supplied to said primaries is 60 cycles per second, the result, because of the arrangement of the primaries noted, is as though a frequency of 180 cycles per second was employed in connection with a single transformer, as will be readily understood.

From the foregoing it will be seen that the current induced in the secondaries 11, 12 and 13, by the action of the primaries 1, 2 and 3, thereupon, will be of like frequency 65 to that of such primaries, and it is to be un-

derstood that such current will flow through the condensers 35, 36 and 37, by the polarization of the armatures, or poles of such condensers and would, by overcoming the dielectric resistance of the spark gaps between the multiple electrodes 32, 33, 34, and 27, 28, 29, cross said gaps and be impressed upon the primary 15, of the air core transformer H, with a frequency like unto, or approximating that of the secondaries 11, 12 and 13, were it not for the inclusion in said gaps, of the rotatable interrupter I, by which such low frequency current, is changed into a high frequency current before it is impressed upon the primary 15, noted, to energize the same and therethrough to energize the secondary 41, of the air core transformer H, which secondary is the source of power of the transmitting, or sonorous circuit C, as will be understood.

Since from the foregoing it will be readily apparent that the change in the current supplied to the circuit B, by the secondaries 11, 12 and 13, from low frequency to high frequency pulsations, is wholly due to the action thereupon of the interrupter I, it only remains to explain such action of the interrupter, and the principle which obtains in the operation of the transformer H, to clearly establish the nature of the current which is supplied by the secondary 41, of said transformer H, to the transmitting, or sonorous circuit, and to such end I will here briefly outline the principle above referred to, which may be thus stated, viz: A current which begins, which approaches, or which increases in strength in the primary, induces by said movements an impulse, or current in the secondary, in direction opposite that in the primary and conversely, a current which stops, which retires, or which decreases in strength in the primary, induces by said movements, an impulse, or current in the secondary, in direction the same as that in the primary.

Now since the interrupter I, is made of a non-conducting material, and in such a manner that it alternately obstructs, or breaks, or provides a free passage for the current, or currents of electricity between the multiple electrodes at opposite sides of the spark gaps, in which said interrupter is placed and operates, it follows that the rotation of said interrupter will operate to intermittently obstruct, or break such current with a very great rapidity, and as the current thus interrupted, or broken, is that by which the primary 15, is energized, it will be at once apparent that the current through said primary will be broken each time said interrupter obstructs, or breaks the current crossing the spark gaps, and that, in accordance with the principle, or law above set forth as obtaining in the production of induced currents, each break, or obstruction of cur-

rent through the primary, will induce a high frequency impulse in the secondary, also that successive impulses in said secondary, will be in opposite directions, according to the rise, or the fall of current in the primary.

It will be understood that the time constant of the circuit B, being very small, the rise and fall of current at each make and 10 break of the interrupter, is of very brief duration and the induced current in the secondary is consequently of high frequency.

From the foregoing it will be clearly apparent that a current of high frequency will 15 be induced in the secondary of the air core transformer H, through the action of the interrupter I, and further that such high frequency current, is consequent upon and wholly determined by the number of breaks 20 made in the current which is so acted upon, by said interrupter, to produce the high frequency current noted.

I have found by practice, that currents of very high tension and yielding large sparks, 25 may be readily broken up by the employment of two interrupting disks I, arranged in axial alinement each with the other, and rotated in opposite directions with each other, and that consequently the arrangement here noted, is peculiarly applicable in 30 cases where, for any reason, currents of the character above noted, are to be used and broken up.

In Figs. 7 and 8, I have shown, in the one 35 instance Fig. 7, a portion of a single interrupting disk I, placed and moving in the direction of the arrow r, between opposing multiple electrodes, and in the latter named Fig. 8, a portion of each of two disks arranged in axial alinement with each other 40 and moving respectively in the directions indicated by the arrows s and t, between opposing multiple point electrodes, and in each of said Figs. 7 and 8, I have indicated by 45 dotted lines, the appearance presented by the interrupted current under the action of the disk and disks, in each instance a stream of sparks follow the disks upon each side of each thereof, in the plane of the apertures formed therethrough, for a distance which, 50 apparently is determined solely by the rate of speed at which said disks move.

In Figs. 11, 12 and 13, I have shown 55 peculiarly formed coils, which, while particularly designed for use in connection with wireless systems of transmission, are yet, to all intents and purposes transformers, in that they meet and fulfil the conditions which obtain in transformers of ordinary 60 construction.

The coils noted, are named in the order in which they are shown, as a "bipolar resonator", a "unipolar resonator", and a "tuning coil", and it is to be understood that that 65 part of each of said coils, which is embraced

between the points u and v, at which the leads y, are connected to said coils, operate as the primary, while the parts outside the points named operate as the secondary of an air core transformer.

70

In Fig. 14, I have shown in diagrammatic form, a modification of the current transforming, or secondary circuit B, the same consisting in confining said circuit solely to the conductors wherein the secondaries 11, 12 and 13, are included, and the direct connection of the same, by a single wire w, with the antenna, in which form, as will be observed, the return conductor 14, and primary 15, of the transformer H, which are 80 included in the circuit B, as illustrated in Fig. 1, does not appear.

75

While I have herein shown my preferred embodiment of my invention, I yet do not desire to confine myself solely to the particular arrangement and combination of parts set forth in such embodiment, since different arrangements and combination thereof might be devised and made, for the purpose of attaining the end sought by this 90 invention, which end is the production of continuous high frequency oscillations in the secondary of an air core transformer, and I therefore claim the right to make any and every modification of this present invention, 95 that shall properly fall within its scope and limit.

95

Having thus described my invention, I claim and desire to secure by Letters Patent, 100

1. In a system for producing electrical oscillations of high frequency an oscillatory circuit including the secondaries of a plurality of step up transformers and the primary of an air core transformer, a spark gap included in the circuit between each of said step up transformers and said air core transformer, a source of electrical energy for successively energizing each of said step up transformers, means comprising an 105 apertured device common to each of the spark gaps, and means to move said apertured device to continuously interrupt the current crossing said gaps.

110

2. In a system for producing electrical 115 oscillations of high frequency a generator, a plurality of step up transformers to be successively energized by said generator, a single air core transformer having its primary in circuit with the secondary of each 120 of the step up transformers, a spark gap included in the circuit between each of said step up transformers and the air core transformer, multiple electrodes in each of said circuits at each side of the spark gaps included in said circuits, means comprising an apertured device common to each of the spark gaps for continuously interrupting the current crossing said gaps between the 125 multiple electrodes at each side thereof, 130

and means for rapidly moving said apertured device to interrupt the current crossing said spark gaps.

3. In a system for producing electrical oscillations of high frequency a three phase generator, a plurality of step up transformers to be successively energized each by a single phase of said generator, a condenser in circuit with each of said step up 10 transformers to be charged by said generator, a spark gap in series with each of said condensers, a single air core transformer common to and having its primary in circuit with each of the secondaries of the step up 15 transformers, a movable dielectric device having apertures formed therethrough to successively pass through each of the spark gaps, and means to rapidly and continuously move said device to interrupt current 20 crossing the gaps.

4. A three phase generator, independent step up transformers each having its primary energized by one phase of current from said generator, an air core 25 transformer having its primary in circuit with the secondaries of the step up transformers, a condenser in each of the circuits between the air core transformer and the secondaries of the step up 30 transformers, a spark gap in each of said circuits in series with the condenser therein, a movable device common to each of the spark gaps in the circuits and provided with apertures, and means to rapidly move said device to 35 continuously interrupt the current crossing the spark gaps.

5. A three phase generator, independent step up transformers each connected to be energized by a single phase of said 40 generator, an air core transformer having its primary in circuit with the secondaries of said step up transformers, a rotatable apertured disk common to and included in the circuit between each of the secondaries of 45 the step up transformer and the primary of the air core transformer, and means to rotate said apertured disk to continuously interrupt the current between said step up 50 transformers and said air core transformer.

6. A three phase generator, independent step up transformers each connected to be energized by a single phase of said generator, an air core transformer having its primary in circuit with the secondaries of said 55 step up transformers, a spark gap included in each circuit between the step up transformers and the air core transformer, a rotatable apertured disk common to each of said spark gaps and means to rapidly rotate said disk to continuously and rapidly 60 interrupt the current crossing said spark gaps.

7. A three phase generator, independent step up transformers each connected to be 65 energized by a single phase of said gen-

erator, an air core transformer having its primary in circuit with the secondaries of said step up transformers, a condenser included in the circuit between each step up transformer and the air core transformer 70 and connected to be energized by conduction and induction, a spark gap included in each of said circuits in series with the condenser therein, a rotatable apertured disk common to each of said spark gaps, and means to 75 rapidly rotate said disk to continuously interrupt the current between the step up transformers and the air core transformer.

8. A three phase generator, independent step up transformers each connected to be 80 energized by a single phase of said generator, an air core transformer having its primary in circuit with the secondary of each of the step up transformers, a condenser included in the circuit between each step up 85 transformer and the air core transformer, a spark gap included in each of said circuits in series with the condenser therein, a plurality of oppositely moving disks arranged in parallel planes and common to all the 90 spark gaps each of said disks having apertures to be brought into alinement with the apertures of the other disk, and means to rapidly rotate said disks in opposite directions to successively move the apertures of 95 said disks into alinement to continuously interrupt the current crossing the spark gaps.

9. In a system for producing electrical oscillations of high frequency and in combination a three phase generator, a plurality of step up transformers each connected to be energized by a single phase of said generator, an air core transformer, an oscillatory circuit including the secondary of each 100 of the step up transformers and the primary of the air core transformer said circuit having spark gaps formed therein between each of said secondaries of the step up 105 transformers and the primary of the air core 110 transformer, a rotatable disk of non-conducting material having apertures formed therethrough equidistant from the axis of said disk and said disk connected to be moved in the gaps formed in the circuit, means connected to bring the apertures of the disk into alinement with the electrodes of each 115 circuit to close circuit through the apertures and means to rapidly rotate said disk to produce a high frequency current in the secondary of the air core transformer.

10. The combination in apparatus for producing high frequency oscillations of a three phase generator, independent step up 120 transformers each having its primary energized by one phase of said generator, an air core transformer, an oscillatory circuit including the secondary of each of the step up 125 transformers the primary of the air core transformer the spark gaps and a condenser 130

- in series with each of said spark gaps, a multiple electrode upon each of the conductors comprised in the circuit at each side of the spark gaps, an interrupter comprising an apertured rotatable disk to move in the spark gaps between the multiple electrodes, and means to rotate said disk to rapidly and continuously interrupt current across the gaps between the multiple electrodes.
11. In a system for producing and transmitting electrical oscillations a generating circuit including a three phase generator and the primary of a step up transformer in circuit with each phase of said generator, an oscillatory circuit including the secondary of each of said step up transformers the primary of an air core transformer in circuit with each of said secondaries a spark gap in circuit with each of said secondaries and an interrupter common to gaps to be moved to interrupt current across said gaps, means to rapidly move said interrupter through said gaps to interrupt current crossing said gaps, and a sonorous circuit including the secondary of the air core transformer the transmitting antenna and an interrupting device interposed in said antenna.
12. In a system for producing electrical oscillations of high frequency a plurality of primary circuits each thereof including the primary of a step up transformer and connected to be energized by one phase of a polyphase current generator of electricity common to each of said circuits, a plurality of secondary circuits each thereof including the secondary of a step up transformer a spark gap and a condenser interposed between and in series with said secondary and said spark gap and each of said circuits connected to energize the primary of an air core transformer common to each of said circuits, and a current interrupting device common to each of the spark gaps of the secondary circuits and connected to interpose in succession solid dielectric mediums moving at a rapid predetermined speed and at equal intervals of time between the opposite poles of each of said spark gaps to interrupt current passing thereacross.
13. In a system for producing and transmitting electrical oscillations of high frequency a plurality of primary circuits each thereof including the primary of a step up transformer and connected to be energized by one phase of a polyphase current generator of electricity common to each of said
- circuits, a plurality of secondary circuits each thereof including the secondary of a step up transformer a spark gap and a condenser interposed between and in series with said secondary and said spark gap and each of said circuits connected to energize the primary of an air core transformer common to each of said circuits, a current interrupting device common to each of the spark gaps of the secondary circuits and connected to interpose successive solid dielectric mediums moving at a predetermined speed and at equal intervals of time between the opposite poles of each of said spark gaps to interrupt current passing thereacross, and a transmitting circuit including the secondary of an air core transformer transmitting antenna and current interrupting devices interposed in said antenna.
14. In a system for producing and transmitting electrical oscillations of high frequency a plurality of primary circuits each thereof including the primary of a step up transformer and connected to be energized by one phase of a polyphase current generator of electricity common to each of said circuits, a plurality of secondary circuits each thereof including the secondary of a step up transformer and a condenser in series with said secondary and each of said circuits connected to energize the primary of an air core transformer common to each of said circuits, a spark gap included in each of said secondary circuits in series with the condenser therein and having each of its opposite electrodes provided with a plurality of terminal points to project into proximity to a current interrupting device placed to move in said spark gaps, a current interrupting device common to each of the spark gaps and connected to interpose successive portions of a solid dielectric medium between the terminal points of the opposite electrodes of each of the spark gaps at a high speed and at equal intervals of time to interrupt current passing thereacross, and a transmitting circuit including the secondary of an air core transformer transmitting antenna and current interrupting devices interposed in said antenna.
- In testimony whereof, I hereto affix my signature in presence of two witnesses.

DAVID G. McCAA.
